REFRIGERATOR

Donald E. Dailey, Center Township, Vanderburgh County, Ind., assignor to Servel, Inc., New York, N. Y., a corporation of Delaware

Application November 9, 1951, Serial No. 17,345

Term of patent 14 years

(Cl. D67—3)

To all whom it may concern:

Be it known that I, Donald E. Dailey, a citizen of the United States of America, residing at Old Petersburg Road, Center Township, in the county of Vanderburgh and State of Indiana, have invented a new, original, and ornamental Design for a Refrigerator, of which the following is a specification, reference being had to the accompanying drawing, forming part thereof.

Fig. 1 is a perspective view showing the top, front and one side of a refrigerator embodying my new design;

Fig. 2 is a perspective view showing the top, side and rear of the refrigerator; and

Fig. 3 is a perspective view similar to Fig. 1 showing the door in open position.

I claim:

The ornamental design for a refrigerator, as shown.

DONALD E. DAILEY.
